Patented Apr. 8, 1958

182,477

TYPEWRITER PAD

Robert L. Mitchell, Los Angeles, Calif.

Application June 14, 1957, Serial No. 46,605

Term of patent 14 years

(Cl. D9—6)

I claim:

The ornamental design for a typewriter pad, substantially as shown.
